Application March 3, 1942, Serial No. 433,181
In Canada January 17, 1942

11 Claims. (Cl. 36—70)

This invention relates to improvements in the heels of footwear, the latter including the classes known generally as shoes and all protective coverings for shoes such as rubbers and overshoes, and consists essentially of a heel tread or top lift having a forwardly extending tongue or flap and a laterally extending ledge or shelf on the inner side.

The principal object of the invention is to provide means in footwear to prevent drip from the footwear which accumulates from traversing wet surfaces from being thrown from the heel of the footwear on one foot of the wearer to the back of the leg belonging to the opposite foot.

Contrary to general opinion, the rain and mud stains observed particularly on the backs of the stockings of women while or having walked on wet surfaces are not caused by splash thrown up at the instant of contact of the foot with the walked on surface, or by drip thrown upwardly and rearwardly to the back of the leg belonging to the same foot. In fact, these stains are caused by drip being thrown forwardly by the heel of one foot after having been in contact with the walked on surface onto the leg belonging to the opposite foot while the first foot is passing the second during its progress forward after having been to the ground, and vice versa. The prior art teaches the incorrect cause of the stains mentioned, to wit; that they are caused on the leg belonging to the offending foot, or by the splash of the opposite foot when contacting the walked on surface. In proof that the general theory is incorrect, a person has been shod on one foot with ordinary footwear and on the other with the present invention, with the invariable result that the leg belonging to the foot equipped with the ordinary footwear is clean, while that equipped with the invention is soiled.

Another important object of the invention is to provide a device of the class described which will be inconspicuous and pass unnoticed to the casual observer; in fact, will not be noticeable at all as a departure from the general or conventional type of footwear.

Still a further important object is to provide a device of this kind which will be simple, and inexpensive to produce and purchase.

With the above and other objects in view as will be hereinafter apparent, the invention consists in general of certain novel details of construction and combinations of parts hereinafter fully described, illustrated in the accompanying drawing and specifically claimed.

In the accompanying drawing like characters 55

of reference indicate like parts in the several views, and:

Figure 1 is a side elevation in part of an article of footwear showing a heel constructed in accordance with the present invention.

Figure 2 is a bottom view of the structure of Figure 1.

Figure 3 is a cross sectional view of the improved heel taken on the line 3—3 of Figure 1.

Referring now to the drawing, the heel belonging to the article of footwear shown thereon is indicated by 10, the shank being indicated by the reference character 13, while the sole of the shoe is shown at 16. In its present embodiment, the invention consists of a forwardly extending tongue 11 which is preferably an integral part of the heel tread or top lift 12 and on a common plane therewith, particularly the tread surface. In plan, the free end of the tongue 11 is pointed, as at 14, that is to say, the lateral edges of the tongue curve inwardly and merge in a point or apex.

The tongue 11, moreover, extends laterally, at least on the inner side of the heel, or that side which is next to the opposite foot of the wearer, to form a ledge or shelf 15 protruding from the juxtaposed vertical plane of the heel 10.

In walking in wet weather with conventional footwear it might be said there are two conditions to which the footwear is submitted:

First, the walked on surface may only be wet, and then only the bottom of the tread becomes wet.

Second, the wearer may be walking through slush or puddles when a good proportion of the entire heel is immersed each step.

In the first instance the water picked up by the bottom of the tread after contact with the wet surface flows by molecular attraction down the bottom of the tread when the foot is raised to the angular position behind the other, and off the tread at the forward corners of the heel. However there is invariably the remaining drop or two, and it is these drops which are thrown to the leg belonging to the opposite foot while the first foot is passing the other in its forward movement.

In the second instance, the condition in which the heel is partially or perhaps wholly immersed, the water flows after the immersion down the heel and underneath it to the under-surface of the tread. Here again is the invariable drop or two of water which is thrown to the back of the opposite leg.

The operation of the present invention is as follows:

In the first instance, the water picked up by the

bottom of the tread flows down the bottom thereof clean to the point 14 of the tongue 11 where the remaining drop or two, or discharge is directed substantially parallel with the path normally taken by the foot during its advanced movement, instead of those drops being thrown laterally to the opposite leg.

In the second condition of walking, when the heel is wholly or partially immersed, the water, after each immersion, flows downwardly along the heel, and on the side thereof next to the opposite foot it is interrupted by the ledge 15, flows along the ledge and thence along the upper surface of the tongue and to the ground. Similarly, the remaining drops will be discharged parallel with the path of the foot, as in the first described instance.

Under no circumstances then is one leg of the wearer soiled by the footwear on the opposite leg.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

I claim:

1. In an article of footwear which includes a shank portion and a heel tread, a tongue on the heel tread and extending in advance thereof and free of the shank portion, the bottom surfaces 35 of the heel tread and tongue being on a common plane.

2. The device according to claim 1, wherein the free end of the tongue terminates in a point, said point being located beneath the shank portion and in a zone removed from the side of the article of footwear which when said article is worn as a member of a pair lies next the other member.

3. In an article of footwear which includes a shank portion and a heel, a tongue on the heel and extending forwardly thereof and free of the shank portion, the bottom surfaces of the heel and tongue being on a common plane.

4. The device according to claim 3, wherein the free end of the tongue terminates in a point, said point being located beneath the shank portion and in a zone removed from the side of the article of footwear which when said article is worn as a member of a pair lies next the other member.

5. In an article of footwear which includes a shank portion and a heel, a tongue on the heel and extending forwardly thereof and free of the shank portion, the bottom surfaces of the heel and tongue being on a common plane, a ledge on the side of the heel which when the article of footwear is worn as a member of a pair lies next the heel of the other member, the bottom surface of said ledge being on a plane common to that of the heel and tongue.

6. The device according to claim 5, wherein the free end of the tongue terminates in a point, said point being located beneath the shank portion and in a zone removed from the side of the article of footwear having the ledge on the heel thereof.

7. In an article of footwear which includes a shank portion and a heel, a tongue on the heel and extending forwardly thereof and free of the shank portion, a ledge on the side of the heel which when the article of footwear is worn as a member of a pair lies next the heel of the other member, the upper surface of said ledge and the upper surface of said tongue being in communication.

8. The device according to claim 7, wherein the free end of the tongue terminates in a point, said point being located beneath the shank portion and in a zone removed from the side of the article of footwear having the ledge on the heel thereof.

9. In an article of footwear which includes a shank portion, and a heel portion having the normal propensity of acquiring a coating of moisture when the foot of the wearer of the footwear is set down and the footwear exposed to moisture during the course of a pace, of lifting the moisture in the form of drip when the foot is raised subsequently to being set down in the course of a pace, and of precipitating the drip ahead but diagonally of the path normally taken by the foot during its advance movement in a pace and diagonally of the longitudinal median line of the footwear, pointed means associated with the heel portion and extending forwardly under the shank portion and free of the shank portion whereby the said direction of precipitation of the drip is directed to a direction substantially parallel with the path normally taken by the foot during its advance movement.

10. In an article of footwear which includes a shank portion, and a heel portion having the normal propensity of acquiring a coating of moisture when the foot of the wearer of the footwear is set down and the footwear exposed to moisture during the course of a pace, of lifting the moisture in the form of drip when the foot is raised subsequently to being set down in the course of a pace, and of precipitating the drip ahead during the advance movement of the foot in a pace, pointed means associated with the heel portion and extending forwardly under the shank portion and free of the shank portion whereby the precipitation of the drip is directed substantially parallel with the path normally taken by the foot during its advance movement.

11. In an article of footwear which includes a shank portion and a heel portion, a pointed device on the heel portion extending therefrom in the zone of the breast of the heel portion and free of the shank portion, the bottom surfaces of the heel portion and said pointed device being substantially on a common plane.
